(57) **CLAIM**

The ornamental design for a beverage chiller, as shown and described.

DESCRIPTION

FIG. 1 is a top-side perspective view of a beverage chiller showing my new design;

FIG. 2 is a bottom-side perspective view;

FIG. 3 is a front elevational view, with the rear elevational view the same;

FIG. 4 is a left side elevational view, with the right side elevational view being a mirror image;

FIG. 5 is a top plan view; and

FIG. 6 is a bottom plan view; and

FIG. 7 is a top-side perspective view of another beverage chiller showing my new design;

FIG. 8 is a bottom-side perspective view of the beverage chiller of FIG. 7;

FIG. 9 is a front elevational view, with the rear elevational view the same, of the beverage chiller of FIG. 7;

FIG. 10 is a left side elevational view, with the right side elevational view being a mirror image, of the beverage chiller of FIG. 7;

FIG. 11 is a top plan view of the beverage chiller of FIG. 7; and,

FIG. 12 is a bottom plan view of the beverage chiller of FIG. 7.

1 Claim, 6 Drawing Sheets
